UNITED STATES PATENT OFFICE.

PETER E. APGAR, OF PHILADELPHIA, PENNSYLVANIA.

DESIGN FOR A VALVE-BODY.

SPECIFICATION forming part of Design No. 32,497, dated April 10, 1900.

Application filed March 9, 1900. Serial No. 8,084. Term of patent 7 years.

To all whom it may concern:

Be it known that I, PETER E. APGAR, a citizen of the United States of America, and a resident of Philadelphia, in the county of Philadelphia, State of Pennsylvania, have invented a new and original Design for a Valve-Body, of which the following is a specification.

My invention relates to a new and original design for a valve-body, and is more particularly adapted to that class of valves known as "three-way" valves and used in conjunction with steam-engine indicators.

Referring to the accompanying drawings, forming part of this specification, Figure 1 illustrates a plan view of the valve-body, showing the arrangement of the parts or openings with respect to the branches. Fig. 2 represents a side elevation of Fig. 1.

As illustrated in the drawings, the leading or material feature of my design consists of a substantially-spherical central portion A, provided with a conical opening A' to receive a valve-stem and having branches B, B', and B'', disposed at right angles to each other. The

branches B and B', which are preferably the 25 inlet branches, are arranged upon a line some distance from the center line c of the opening A', as shown in Fig. 1, while the branch B'' is arranged upon a line passing directly through the center line of the opening A', so that while 30 the branches B, B', and B'', as before stated, are arranged at right angles the openings b, b', and b'' in the branches will intersect the opening A' at points an equal distance apart, and thus providing by this particular design 35 of valve-body the greatest possible amount of lap for the stem of the valve.

Having described my invention, what I claim as new, and desire to secure by Letters Patent, is—

The design for a valve-body substantially as herein shown and described.

Signed at Philadelphia, Pennsylvania, this 23d day of February, 1900.

PETER E. APGAR.
